UNITED STATES PATENT OFFICE.

OTTO L. HERMANN, OF ST. LOUIS, MISSOURI, ASSIGNOR TO CORBON L. HARVEY, OF DETROIT, MICHIGAN.

LEDGER RACK.

Application filed February 2, 1923. Serial No. 616,527.

To all whom it may concern:

Be it known that I, OTTO L. HERMANN, a citizen of the United States, residing at St. Louis, Missouri, have invented a certain new and useful Improvement in Ledger Racks, of which the following is a full, clear, and exact description, such as will enable others skilled in the art to which it appertains to make and use the same, reference being had to the accompanying drawings, forming part of this application.

My invention relates to racks for loose leaf ledgers of the general type shown and described in Patent No. 1,367,875, issued to C. L. Harvey February 8, 1921, and consists in improvements upon racks of this type which facilitate the turning of ledger leaves. Ledgers of this type have two or more binding posts and the ledger leaves are perforated to slip over these posts. The ledger sheets are usually removed for entering items on a typewriter, bookkeeping or billing machine and are then assembled with each other and the binder by dropping the leaves with their perforations over the binding posts. Generally a number of sheets will be turned from the back to the front of the ledger without any entry being made and it is rather difficult to turn these sheets without disturbing the alignment of their perforations.

The main object of my invention is to provide in a rack upon which the ledger is supported during the posting operation, means for preventing shifting of the ledger and a guiding member which eliminates the disalignment of the perforations in the leaves as they are turned and the delay incident thereto.

A common plan of posting entries in ledgers of this type is to offset the leaves upon which entries are made so that after the entries are completed, the ledger may be examined for a summary of the day's business by running through the offset leaves.

Another object of my invention is to adapt the rack for accommodating the ledger when this offset-leaf-plan is in use without necessitating the construction of a different rack, and as a result thereof the stocking of two different styles of racks where one style is sufficient.

In the accompanying drawings which illustrate a selected embodiment of my invention,

Figure 1 is a top view of my improved

rack with a ledger mounted thereon, the ledger backs or covers and leaves being shown in dot and dash lines.

Figure 2 is a front elevation of the same.

Figure 3 is an end elevation of the same looking toward the lefthand end of Figure 2.

Figure 4 is a fragmentary view on an enlarged scale showing the end of the rack appearing in Figure 3 with the offset posting adjustment member in place.

The rack base 1 is divided into two ledger back supporting surfaces 2 and 3, spaced from each other by a transverse partition 4 against the opposite faces of which the inside edges of the ledger leaves 5 rest. Extending at right angles to partition 4 and at the rear of the rack is a vertical wall 6 which engages the top edges of the ledger leaves. This wall is recessed at 7 adjacent to the horizontal supporting surfaces 2 and 3 to receive the projecting top edge of the ledger back 8 resting upon those surfaces. The height of recess 7 is sufficient to receive the edge of the ledger back but provides frictional contact with the latter so that when the back is inserted in the recess there will be a tendency to resist unintentional removal of the back therefrom. Aligned with the leaf engaging surface of wall 6 and projecting a substantial distance above the same and above partition 4 is a member 9 which serves as a guide for the top edges of the ledger sheets as they are turned either singly or in groups from the righthand side of the ledger to the lefthand, or vice versa. As a brace for member 9 or for ornamental purposes I add a piece 10 which is not essential to the functioning of the rack.

With the construction just described, one or more sheets may be lifted from the extreme righthand edge, turned over partition 4 where they will be supported, and by sliding them against the surface of member 9 and drawing them to the left, over partition 4, they will fall upon the other sheets on the lefthand side of the partition in such a position that their perforations 11 will be aligned with and will fall over the pointed caps 12 provided on the ledger binding post 13. Caps 12 are removable from the post and are only used during the posting operation. At other times they are inserted into holes 14 in the rear wall of the rack.

With the above described construction and

operation, all of the leaves on either side of partition 4 are aligned with each other as well as with the leaves on the opposite side of the partition. If it is desired to use the 5 offset-leaf posting plan referred to above, a spacing member 15 is provided and used as indicated in Figure 4. This member is adapted to slide into recess 7 just the same as the edge of the ledger back. The outer 10 face of member 15 is provided with a rabbeted surface 16 which cooperates with surface 2 of the rack to form a recess corresponding to recess 7 but which when used will hold the lefthand back of the ledger 15 a substantial distance from the rear wall of the rack.

Where this offset posting plan is adopted it will be necessary to provide duplicate 20 perforations in the ledger leaves to accommodate the different relative positions of the sheets and binding posts. As indicated in Figure 4, the leaves 18 upon which entries 25 have been made are reassembled with the ledger by placing perforations 17 over the binding post while the remainder of the leaves are simply turned over without disturbing their original alignment resulting in the posted sheets 18 being offset.

By using member 15, the rack is adapted 30 for either position of the ledger and while it is likely that the same company will not want to use any one ledger in both positions, it may be desirable to use different ledgers in different positions and it 35 certainly would be advantageous for the stationer to be able to supply a customer having either preference with a rack of the type desired, without being compelled to stock additional racks as would be the case 40 if each rack could accommodate the ledger in one position only.

It is desirable that when a ledger is placed on the righthand side of the rack, to be 45 opened, that it may, with the same movement, be pushed into position with the top edge of its back cover in the recess 7. This means that the top edge of the unopened front cover must project over the right-hand portion of wall 6 as the latter is intended to engage the top edges of the leaves. 50

As the number of leaves will vary from time to time it is desirable that the height of the righthand portion of wall 6 be made adjustable and this effect is produced by 55 mounting sectional posts 19 in the top edge of wall 6. Posts 19 are of the type which are used in adjustable ledgers and need no detailed description here. They may be increased or reduced in height by adding or 60 subtracting sections similar to section 20 which has been provided to make the leaf retaining surface correspond to the thickness of the ledger less the front cover.

Other means of securing this result will 65 be suggested to those familiar with similar

devices and I contemplate the use of such modifications and other variations in the details of my device as come within the scope of the appended claims.

I claim:

1. In an open front rack for a loose leaf ledger, ledger supporting surfaces, a central upright partition for engaging the inside edges of the backs and leaves of the open ledger, a relatively low rear wall at right angles to said partition for engaging the top edges of the ledger leaves on both sides of said partition, said wall being recessed near its bottom to receive the top edges of the ledger back projecting beyond the leaves, and a member extending above the top of said partition and wall at the center only of the latter and aligned with said wall for guiding the ledger leaves as they are turned from the back on one side of the partition to the back on the other side thereof. 70

2. In an open front rack for a loose leaf ledger, ledger supporting surfaces, a central upright partition for engaging the inside edges of the backs and leaves of the open ledger, a relatively low rear wall at right angles to said partition for engaging the top edges of the ledger leaves on both sides of said partition, said wall being recessed near its bottom to receive the top edges of the ledger back projecting beyond the leaves, a member extending above the top of said partition and wall at the center only of the latter and aligned with said wall for guiding the ledger leaves as they are turned from the back on one side of the partition to the back on the other side thereof. 80

90

3. In a rack for loose leaf ledgers or the like, a wall for aligning the edges of the leaves of the ledger, said wall being recessed near its bottom to receive the edges of the lower cover of the ledger projecting beyond the edge of the leaves, and means for varying the height of the leaf-aligning surface of said wall so as to accommodate different quantities of sheets in the ledger during successive periods of use of the ledger without interfering with the projecting edge of the top cover of the ledger when the ledger is closed and resting on said rack. 100

110

4. In a rack for an open loose leaf ledger provided with the usual binding posts, spaced ledger back supporting surfaces, a wall perpendicular thereto extending along both ledger backs and adapted to engage the edges of the ledger leaves, and means for laterally adjusting the position of one of the ledger backs and binding posts thereon relative to said wall and the other back whereby leaves of one posting operation may be guided by said wall into position on said first mentioned back so as to be offset relative to the leaves not being posted. 120

125

130

5. In a rack for loose leaf ledgers or the like, a wall for aligning the edges of the leaves of the ledger, said wall being recessed near its bottom to receive the edge of the lower cover of the ledger projecting beyond the edges of the leaves, and posts composed of detachable sections mounted on said wall above said recess and forming an adjustable continuation thereof for varying the height of the leaf-aligning surface so as to accommodate different quantities of sheets in the ledger during successive periods of use of the ledger without interfering with the projecting edge of the top cover when said ledger is closed and resting on said rack.
- 10 6. In a rack for open loose leaf ledgers,

a supporting surface for the ledger backs, a wall for engaging and positioning the top edges of the ledger leaves, said wall being provided with a recess adjacent to said surface for receiving the top edges of the ledger backs which project beyond the top edges of the leaves, and a removable member adapted to be inserted into said recess to space one ledger back a greater distance from said wall than the other ledger back and provided with a ledger back receiving recess corresponding to the wall recess into which the member is inserted.

In testimony whereof I hereunto affix my signature this 30th day of January, 1923.

OTTO L. HERMANN.
